UNITED STATES PATENT OFFICE.

ALVAR K. TERNSTEDT, OF NEW YORK, N. Y., ASSIGNOR TO PERFECT WINDOW REGULATOR COMPANY, OF NEW YORK, N. Y., A CORPORATION OF MAINE.

MECHANICALLY-OPERATED WINDOW.

1,218,130.

Specification of Letters Patent.

Patented Mar. 6, 1917.

Application filed December 12, 1914. Serial No. 876,790.

To all whom it may concern:

Be it known that I, ALVAR K. TERNSTEDT, a subject of the King of Sweden, and a resident of New York, in the county of New

5 York and State of New York, have invented certain new and useful Improvements in Mechanically-Operated Windows, of which the following is a specification.

This invention relates to a construction 10 or means whereby a frameless plate of glass in a mechanically operated window may be quickly and easily replaced when broken.

The object of the invention is to avoid 15 the necessity of removing or disturbing the window operating mechanism in order to get at the broken glass to remove and replace it. It is also the object to effect this result in a simple and practical manner.

The invention consists in the improved 20 construction and arrangement for accomplishing the desired result hereinafter more particularly described and then specified in the claims.

The invention will be herein shown and 25 described as applied to a carriage window such as employed in automobiles in which the window is raised and lowered by mechanical means in contradistinction to the hand operated windows sometimes used but 30 it will be understood that this use of the invention is for the purpose of illustration only and not to be considered as limiting the scope thereof.

The invention is particularly for use in 35 frameless glass constructions, that is, wherein the plate of glass is not surrounded or mounted in a frame traveling with it but the glass *per se* works in suitably formed guides rigidly secured to the pillars of the 40 door or wall in which the window is located.

In the accompanying drawings, Figure 1 is a vertical, central cross-section through a carriage window construction in accordance 45 with this invention, the same being shown as applied to the door of an automobile.

Fig. 2 is a front elevation of the same, the inside upholstery being removed to show the operating-mechanism more clearly.

50 Fig. 3 is a transverse section through one of the side pillars, the glass being removed.

Fig. 4 is a view similar to Fig. 1 showing the parts in position for removing and replacing the glass.

Fig. 5 is a perspective view of the lower 55 part of the glass plate with the detachable plate for the operating mechanism connected thereto.

Fig. 6 is a front elevation of part of the lower casing showing the operating means 60 after being detached from the glass.

Fig. 7 is a vertical central cross-section through the door, the glass and its operating mechanism being removed to show the arrangement of the guiding channels (one 65 side) in which the glass travels.

In the drawings, 1 indicates the outer weather rails, 2 the inner rail or top board of the lower casing 3 in which the operating means are mounted. 4 indicates the head 70 rail of the door and 5 indicates the side pillars of the window opening.

6 indicates a plate of glass forming the closure for the space between the head rail 4, weather rail 1 and pillars 5, the closure in 75 this case being of the frameless glass type, that is, the glass plate is not surrounded by the usual inclosing frame but its side edges are preferably rounded and work in velvet or otherwise suitably lined guides formed 80 in or attached to the pillars 5, the linings for the guides, for clearness, not being shown in the drawings. According to this invention the guides are preferably formed

as U-shaped channels 7. A guiding channel 85 is provided for each side of the glass, but one being shown in the drawings. The guides run from directly beneath the head rail 4 down into the casing 3 and are each divided into preferably two parts, the upper 90 part 7' being of a length somewhat short of the height of the glass plate 6 and a space 8 is left between it and the beginning of the lower guide 7 (see Fig. 7) for purposes to be hereinafter described. Obviously, as 95

the glass 6 is caused to travel it will straddle the space 8. The guides 7 and 7' are suitably secured to the pillars 5, the upper part 7' being preferably fastened by means of lugs 9 integral with or secured to the channel 7' and attached to the pillar by suitable screws.

The upper end of the guide 7' enters a recess 10 in the head rail 4 while the lower end is preferably concealed beneath the upper edge of the top board 2.

The lower edge of the glass plate 6 seats in a U-shaped carrier 11 which is provided

at or about its center with a short length of angle metal 12 suitably secured to and carried by the carrier 11.

The top board 2 has an opening 13 formed through it somewhat wider than the length of the angle piece 12 secured to the carrier 11 and in such position that it will expose the lower edge of the carrier when the glass plate is in closed position as indicated in Fig. 2.

The operating mechanism for mechanically raising and lowering the glass 6 is mounted within the lower casing 3 and is provided with a plate 14 secured to the top board 2 so that its upper edge will be positioned somewhat down from the upper edge of the opening 13, the object being to leave the opening 13 exposed. The plate 14 carries and supports the upper part of the operating means, the lower part being suitably supported near the bottom of the casing 3.

Any suitable type of operating means may be employed but preferably I use the type shown and described in my prior application for patent filed Dec. 19, 1911, Serial No. 666,759, and it is thought that a brief reference to the parts herein is sufficient as the particular type of means employed forms no part of my present invention.

A sprocket-wheel 15 mounted at the back of the plate 14 is provided with an operating handle 16 which projects beyond the inner face of the door. A casing 17 secured to the front of the plate 14 contains the automatic locking mechanism which holds the glass 6 in any desired position in its travel. A driving chain 18 passes over the upper sprocket 15 and a lower sprocket 19 and is caused to travel by turning the handle 16.

The chain 18 carries a laterally projecting stud 20 which engages a slot 21 in a depending plate 22. The plate 22 is detachably secured to the angle piece 12 by means of screws 23. By rotating the handle 16 the chain 18 travels and in its movement it raises or lowers the glass 6 according to the direction of rotation by means of the pin 20 working in the slot 21 of the plate 22, the plate 22 being normally secured to the glass 6 by means of the screws 23.

The inner surface of the door is finished off and the operating means concealed by applying the padding 24 and cloth 25 in a well-known manner. The fastening lugs 9 of the guides 7' are concealed by molding strips 26 or upholstery secured to the pillar 5.

The operation of substituting a new glass is as follows:—Should the glass 6 become broken, the moldings 26 are removed to expose the fastening lugs 9. The upholstery 25 is laid back from above the casing 17 and the padding 24 removed as indicated in Fig. 4. Normally the stud 20 stands in about the

position shown in Fig. 2 when the window is closed and if desired to substitute a new glass, the handle 16 is turned slightly to lower the glass 6 a trifle and cause the pin 20 to travel toward the left of the slot 21 and beyond the center of the plate 22. The fastening screws 23 are then removed and the plate 22 and the operating means are free of the glass 6, the plate 22 falling lengthwise of the chain 18 and to get it out of the way the handle 16 is turned to drop the plate 22 down to about the position shown in Fig. 6. The object in first causing the stud 20 to travel toward the left of the slot 21 before detaching the plate 22 is as follows:—It will be noted that in the right-hand end of the slot 21 is an enlarged opening 30. This is for ease in assembling the operating mechanism, the stud 20 being provided with an enlarged head 31 to engage the back surface of the plate 22 and normally prevent it coming out of the slot. The enlarged head 31 passes, when assembling the construction, through the enlarged opening 30 and to prevent the plate 22 becoming disengaged from the stud when detached from the glass carrier 11, it is moved toward the opposite end of the slot so that the plate will drop into the position shown in Fig. 6 and will not fall off the stud.

The fastening screws of the lugs 9 are now removed and the glass and the guiding channels 7' are free to drop down until the upper ends of the channels are free of the recess 10 in the head rail 4. The glass with its carrier 11 and its channels 7' can then be swung outwardly or transverse to the plane of the glass as indicated in Fig. 4, the position of the operating mechanism remaining undisturbed.

After the glass has been replaced, the reverse operation takes place; to wit, the channels 7' and glass 6 are swung back into place and the lugs 9 fastened to the pillars. The plate 22 is brought up by rotating the handle 16 and again fastened to the carrier 11 by the fastening screws 23 after which the moldings and upholstery are replaced.

In some cases, particularly in automobile doors the head rail 4 instead of being closed as herein shown is provided with an open slot through which the glass can be inserted. In this case it is not necessary to swing the channels in the manner shown in Fig. 4 after detaching the plate 22 from the glass. However, when a sealing device such as indicated at 35 (Figs. 1, 4 and 5) is employed, it is necessary to swing the lower end of the glass slightly to allow the sealing flange to clear the weather rail 1 in withdrawing the glass.

It will be understood that the invention is not limited to the particular arrangement of parts and details of construction as shown in

and described except as may be set forth in the appended claims.

What I claim as my invention is:—

1. In a window construction, the combination with a frame having a window opening therein, a plate of glass for closing said opening, said frame having a walled space below the opening into which the glass may be lowered as the window is opened, mechanical operating means located within said space for moving the glass, a member connected with the glass and devices detachably connecting the operating means with the said member, said devices being within the said space and inaccessible except when a portion of the wall inclosing said space is removed, said devices then being adapted for disconnection so that the glass may be removed without disturbing the operating means.
2. In a window construction, the combination with a frame having a window opening therein, a plate of glass for closing said opening, said frame having a walled space below the window opening into which the

glass may be lowered as the window is opened, edge guides for the glass made in two sections, one section being in the said space and the other being detachably secured within the window opening, mechanical operating means within said space for moving the glass, a member connected with the glass and devices detachably connecting the operating means with the said member, said devices being within the said space and 30 inaccessible except when a portion of the wall inclosing said space is removed, said device then being adapted for disconnection so that when said devices and the upper edge guide sections are disconnected the 35 glass may be removed without disturbing the operating means.

Signed at New York, in the county of New York and State of New York this 11th day of December, A. D. 1914.

ALVAR K. TERNSTEDT.
